ELEVATING MEANS FOR WINDOW SHADES OR BLINDS

Jules Nisenson, 9 Ann Lane, Rye, and Stanley D. Barnett,
11 Winfield Ave., Mount Vernon, N.Y.
Filed Aug. 25, 1960, Ser. No. 51,842
2 Claims. (Cl. 160—133)

This invention relates generally to the field of rollable shades or blinds of a type widely used in the screening of frame windows, and more particularly to an improved elevating and lowering means permitting precise easy operation.

With the increased use of bamboo and other thin wood blinds in lieu of conventional paper or cloth shades, the conventional spring-type shade roller has not proven suitable, owing to the relatively heavy weight of the blind itself which the spring roller is unable to overcome during a lifting operation. Manual cord operation is suitable, but where the blinds are relatively heavy some mechanical advantage must be provided to facilitate movement. While it is possible to use a worm and gear motion transmitting means, in most cases the large scale gear reduction encountered is excessive, so that the raising and lowering of the shade requires a substantial amount of arm movement on the part of the user, which is both time consuming and annoying. On the other hand, if a higher gear reduction is employed, the gear system usually lacks sufficient static friction to maintain the shade in a given adjustment or disposition.

It is therefore among the principal objects of the present invention to provide an improved motion transmitting means whereby a shade may be conveniently raised or lowered with a minimum amount of arm movement on the part of the user, and which will automatically maintain a given adjustment through the action of a gear system which is not reversible from the standpoint of transmitted motion.

Another object of the invention lies in the provision of an improved construction of the class described in which the cost of fabrication may be of a reasonably low order, with consequent wide sale, distribution and use.

Still another object of the invention lies in the provision of an improved gear reduction means which will automatically maintain itself in a locked condition when the blind or shade is not in the process of being adjusted, but will nevertheless require relatively little effort to raise or lower.

A further object of the invention lies in the provision of an improved structure of the class described which may be largely fabricated using stampings and other easily machined parts, and in which close tolerances are unnecessary.

A feature of the invention lies in the fact that the device may be incorporated into existing window sash structures without alteration.

Another feature of the invention lies in the elimination of the necessity of supplementary clutch mechanisms to maintain the blind in a given adjustment.

These objects and features, as well as other incidental ends and advantages, will more fully appear in the progress of the following disclosure, and be pointed out in the appended claims.

In the drawings, to which reference will be made in the specification, similar reference characters have been employed to designate corresponding parts throughout the several views.

FIGURE 1 is a fragmentary view in elevation of an embodiment of the invention.

FIGURE 2 is a vertical sectional view as seen from the plane 2—2 in FIGURE 1.

FIGURE 3 is a vertical sectional view as seen from the plane 3—3 in FIGURE 1.

FIGURE 4 is a fragmentary bottom plan view as seen from the plane 4—4 in FIGURE 1.

FIGURE 5 is a view in perspective of a fixed guide member comprising a part of the embodiment.

FIGURE 6 is an enlarged fragmentary vertical sectional view as seen from the plane 6—6 in FIGURE 3.

FIGURE 7 is a vertical fragmentary sectional view as seen from the plane 7—7 in FIGURE 6.

FIGURE 8 is a vertical sectional view as seen from the plane 8—8 in FIGURE 6.

FIGURE 9 is a vertical sectional view as seen from the plane 9—9 in FIGURE 6.

FIGURE 10 is an enlarged exploded view in perspective, partly broken away to show detail, of the structure shown in FIGURE 6.

FIGURE 11 is a fragmentary view in perspective showing a spider member which comprises a part of the embodiment.

In accordance with the invention, the device, generally indicated by reference character 10, is supported by conventional anchor bracket elements 11 and 12 to a window frame 13 in well known manner by screws 14 or other suitable attaching devices. Disposed between the bracket elements 11 and 12 is a shade or blind roller 15 preferably of hollow configuration. The roller 15 mounts a short stub shaft 16 engaging the bracket 11, and at the opposite end there is a corresponding stub shaft 17 having a non-circular outer portion engaging the bracket 12.

The roller 15 includes an elongated tubular member 18 having an outer surface 19 around which the blind 18' is wound, and an inner surface 20. A left-hand retaining flange 21 is mounted adjacent the shaft 16, including an outer surface 22 and an inner surface 23. A stationary guide 24 (best seen in FIGURE 5) is slidably disposed on the outer surface 19, the same including an arcuate portion 25 having an outer edge 26 and an inner edge 27, as well as a depending portion 28 having a laterally extending flange 29 engaging a corresponding extension 30 on the bracket element 11. From a consideration of FIGURE 1, it will be apparent that as the roller 15 turns, the guide 24 will be maintained in relatively fixed position, so as to provide a stationary inner surface 34 for the purpose of guiding the edge of the blind 18'.

Referring to the right-hand portion of FIGURE 1, there is provided a pulley 36 driven by a cord 37 maintained upon the stub shaft 17 by a snap ring 38 (see FIGURE 6). The pulley includes an eccentrically disposed bore 39 as well as a centrally disposed bore 40. The stub shaft 17 includes a flattened portion 41 engageable within the bracket element 12, a first cylindrical portion 42, a toothed portion 43, and a second cylindrical portion 44, the inner end portion 45 of which is adapted to be staked.

Surrounding the first cylindrical portion 42 and extending up to the staked end 45 is a hollow spider or cage 47. As best seen in FIGURE 10, the spider 47 includes first and second end plates 48 and 49, respectively, having openings 50 and 51, respectively, and being interconnected by a bridge member 52.

Referring to FIGURE 6, a shaped pintle 54 engages the bore 39, and provides for the transmission of rotational motion from the pulley 36 to the spider 47. A pair of aligned openings 57 and 58 provide bearings for a small gear 59 engaging the toothed portion 43 which forms a fixed or sun gear. As best seen in FIGURE 6, the gear 59 includes stub shafts 60 and 61 engageable within the openings 57 and 58, respectively.

Surrounding the spider 47 is an outer housing 62,

including a cylindrical portion 63 having a circular end wall 65. The end wall 65 is provided with a small centrally disposed bore 66, which extends through a cylindrical member 67 forming a bearing engaging the second cylindrical portion 44 of the shaft 17. The outer surface of the cylindrical member 67 forms a toothed gear 68 coaxially aligned with respect to the toothed gear portion 43, and having one less tooth than the portion 43. The outer surface 69 of the housing 62 is preferably of a diameter to permit a force fit with respect to the inner surface 20 of the roller 15.

Referring to FIGURE 1, a stationary guide 70 is provided at the driven end of the device corresponding identically to the stationary guide 24, the same having a projecting portion 71 engageable with the cord guide means 72.

Movement of the cord 37 results in motion being transmitted through the pulley 36, to the spider 47, wherein the gear 59 executes planetary motion about the toothed gear portion 43. As the gear 68 has one less tooth than the portion 43, a mechanical advantage equal to the number of teeth present on the gear 68 will be obtained.

Although the mechanical advantage is substantially less than that obtained by a worm drive, it is normally adequate to prevent reverse motion being transmitted back to the pulley, that is to say in which the shade or blind would unwind itself. This self-locking action is not due to the degree of mechanical advantage along, but to the fact that the torque arm of the gear 68 is proportionately less than the combined torque arms of the portions 43 and 59 through which a reverse force must be transmitted, as compared with the actual mechanical advantage obtained.

We wish it to be understood that we do not consider the invention limited to the precise details of structure shown and set forth in this specification, for obvious modifications will occur to those skilled in the art to which the invention pertains.

We claim:

1. In a device for adjustably supporting a window shade or blind, a generally horizontally disposed roller, bracket means supporting said roller for rotation at at least one end thereof, stationary guide means surrounding said roller at said end, said guide means including an annular surface disposed substantially perpendicular to the axis of said roller and extending radially therefrom, said guide means directly engaging said bracket means whereby said guide means is maintained substantially immobile during rotation of said roller.
2. In a device for adjustably supporting a window shade or blind, a generally horizontally disposed roller, bracket means supporting said roller for rotation at a first end thereof, stationary guide means surrounding said roller at said end, said guide means including an annular surface disposed substantially perpendicular to the axis of said roller and extending radially therefrom, said guide means directly engaging said bracket means whereby said guide means is maintained substantially immobile during rotation of said roller; stationary cord guide means associated with said roller at a second oposite end thereof, second stationary guide means surrounding said roller at said second end thereof, said second guide means engaging said cord guide means whereby said second guide means is maintained substantially immobile during transmission of motion to said roller.
